UNITED STATES PATENT OFFICE.

MAUD M. SEY, OF GREENBUSH, MICHIGAN.

SKIRT-SUPPORTER.

1,160,536.

Specification of Letters Patent. Patented Nov. 16, 1915.

Application filed March 24, 1915. Serial No. 16,717.

To all whom it may concern:

Be it known that I, MAUD M. SEY, a citizen of the United States, residing at Greenbush, in the county of Alcona and State of Michigan, have invented certain new and useful Improvements in Skirt-Supporters, of which the following is a specification, reference being had to the accompanying drawings.

10 My invention relates broadly to new and useful improvements in garment supporters and has particular reference to devices of this character which are especially adapted to be used in supporting skirts.

15 The principal object of the invention is to provide a skirt supporter consisting in a pair of straps, the rear terminals of which are designed to be detachably connected to the skirt band and the forward terminals 20 of which are connected and accompanied by an eyelet which may be connected to the top fastening stud of the user's corset, whereby the weight of the skirt will be borne by the shoulders, instead of by the 25 wearer's waist.

Another object is to fasten the supporter so that it will be linearly adjustable, thereby adapting it for use by persons having different length trunks.

30 The above, and other incidental objects of a similar nature, which will be herein-after more specifically treated, are accomplished by such means as are illustrated in the accompanying drawings, described in 35 the following specification and then more particularly pointed out in the claims which are appended hereto and form part of this application.

With reference to the drawings, wherein 40 there has been illustrated the preferred embodiment of this invention as it is reduced to practice, and throughout the several views of which similar reference numerals designate corresponding parts, Figure 1 is a perspective view showing the skirt supporter applied; Fig. 2 is a perspective view illustrating the supporter in detail; Fig. 3 is a section taken transversely through the stiffening bar; Fig. 4 is a detail perspective view 45 showing the manner in which the fabric and sheathing strip is applied to the stiffening strip; and Fig. 5 is a longitudinal section taken through the stiffening bar.

50 As embodied in the accompanying drawings and as best shown in detail in Fig. 2 thereof, the skirt supporter includes a pair

of suspended straps 10 and 11, each of which is formed in two adjustable sections connected by snap buckles 12. These straps 10 and 11 are adapted to pass over the shoulders of the wearer and to be attached at their rear ends to the skirt and at their front ends to the wearer's corset. The front ends of the straps 10 and 11 are stitched or otherwise attached to a looped strap 13, the lower 55 portion of which passes through an eyelet 14. This eyelet 14 is adapted to be attached to the top stud or fastening device of the corset, of the wearer, as best shown in Fig. 1. The rear terminals of the straps are 60 stitched or otherwise secured to a sheathing 15 which incases a whalebone stiffening strip 16. The straps 10 and 11 and the transverse strap 17, which connects them adjacent their lower terminals and serves to hold 65 them against undue separation, are preferably made from elastic bands of the interwoven cloth and rubber type, such as are employed in making garters and suspenders and the like. To the sheathing 15 of the 70 stiffening strip and at the terminals of this member, are secured fasteners 18 which are of the rubber covered stud type, ordinarily employed in garters and the like. Through the slots in the body portions of these fasteners, is passed the piece of cloth which, 75 when sewed on the stiffening strip, constitutes the sheathing 15.

When the supporter is in use, the fasteners 80 18 are engaged with the eyelets 20, which are secured to the back of the waist band of the skirt and on the inner face thereof. The straps are then passed over the wearer's shoulders and the eyelet 14 is engaged with the top hook of the corset, as disclosed in 85 Fig. 1. Thus the entire weight of the skirt is supported by the wearer's shoulders, instead of by the hips. The studs or fastening devices may be employed as a means for holding the shirt-waist against withdrawal 90 from the skirt band by passing the studs through button-holes 21 formed in the waistband of the waist, as shown in Fig. 2. In this connection, it will of course be appreciated that the stiffening strip lies beneath 95 the waist.

In reduction to practice, it has been found that the form of this invention illustrated in the drawings and referred to in the above description as the preferred embodiment, is the most efficient and practical; yet realizing 100 that the conditions concurrent with the 105

adoption of this device will necessarily vary, it is desirable to emphasize the fact that various minor changes in details of construction, proportion and arrangement of parts may be resorted to, when required, without sacrificing any of the advantages of this invention, as defined by the appended claims.

What is claimed is:—

1. In a skirt supporter adapted to be suspended from the wearer's corset, a pair of skirt supporting straps, an eyelet for attaching the terminals of the straps to the fastening device of the wearer's corset, a transverse strap connecting the skirt supporting straps adjacent their lower terminals for preventing the undue separation of the skirt supporting straps, a stiffening strip connecting the lower terminals of the skirt supporting straps, a strip of fabric ensheathing the stiffening strip, said skirt supporting straps being stitched to the fabric strip, and a pair of fastening studs secured to the ensheathing strip of fabric, said fastening

studs being adapted to receive eyelets carried by the waist-band of the wearer's skirt 25 for supporting the skirt.

2. In a skirt supporter adapted to be suspended from the wearer's corset, a pair of lineally adjustable strap members adapted to be passed rearwardly over the wearer's shoulders, an eyelet connected to the front terminals of the strap members, said eyelet being adapted to engage the fastening device of the wearer's corset for attaching the straps thereto, and fastening studs carried by the rear ends of the straps for engagement with the waist-band of a skirt, where 30 by the weight of the skirt is borne by the wearer's shoulders.

In testimony whereof I hereunto affix my 40 signature in the presence of two witnesses.

MAUD M. SEY.
